SAFETY OAR LOCK AND SUSPENDER

Anthony Skindel and Owen J. Gillespie,
Villas, N. J.

Application April 24, 1933, Serial No. 667,524

6 Claims. (Cl. 9—26)

Our invention relates to new and useful improvements in a safety oar lock and suspender and has for one of its objects to generally improve the construction of devices of this kind for 5 flexibly suspending an oar in a manner that the friction on the parts will be reduced to a minimum.

Another object of the invention is to provide 10 simple and effective means for adjusting the height of the oar within the oar lock.

Another object of the invention is to provide 15 means whereby the flexible part of the suspender will have two points of connection with the clamp or cradle which holds the oar.

18 A further object of the invention is to provide simple and effective means for removably mounting the oar lock in a socket carried by the gunnel of the boat.

20 A still further object of the invention is to provide in combination, a socket member to receive the shank of the oar lock which will be removably held in place by a screw having threaded connection with the socket and projecting into a circular groove in the oar lock shank, the body 25 of said oar lock being of oval shape with the smaller end upward and providing a closed eye within which a pair of guideways are formed to receive the ends of a vertically adjustable block, the latter being carried by a screw projecting 30 through a hub at the upper end of the oar lock and held in different adjusted positions by a nut screwed thereon, said adjustable block having one end of each of two chains connected therewith while the opposite ends are attached at separated 35 locations to a clamp or cradle hung by said chains within the closed eye of the oar lock, said clamp receiving and temporarily fixedly holding an oar.

40 With these and other ends in view, this invention consists in the details of construction and combination of elements hereinafter set forth and then specifically designated by the claims.

45 In order that those skilled in the art to which this invention appertains may understand how to make and use the same, we will describe its construction in detail, referring by numerals to the accompanying drawing forming a part of this application, in which:—

50 Fig. 1 is a view partly in elevation and partly in section showing our improved safety oar lock and suspender mounted in a socket on the gunnel of a row boat and a section of the oar in the clamp or cradle.

55 Fig. 2 is a view at right angles to Fig. 1, with

a part of the oar lock broken out to illustrate details of construction.

Fig. 3 is an enlarged sectional view on the line 3—3 of Fig. 1.

In carrying out our invention as herein embodied, 5 represents, conventionally, the gunnel of a row boat having a vertical hole therethrough for the reception of the depending socket 7 of the socket member 8 which also includes a flange 9 to rest upon the upper edge of the boat gunnel and be secured in place by suitable fastening devices 10, such as screws.

The oar lock 11 includes an oval shaped body 12 with the larger end lowermost, and from said larger end projects a shank 13 fitted into the socket 7 where it will be held by a set screw 14 threaded through the socket 7 with its inner end projecting into the circular groove 15 formed about the outside of the shank 13. Between the shank and the body of the oar lock is formed a shoulder 16 which rests upon the uppermost face of the socket member 8.

At the upper or smaller end of the oar lock body is formed a hub 17 having a vertical hole 18 therethrough through which projects a screw or threaded rod 19 with a nut 20 screwed thereon for holding the screw or threaded rod 19 in any desirable vertical adjustment. The lower or inner end of said screw or threaded bolt 19 carries an adjusting block 21, somewhat narrower than the walls of the body of the oar lock, and said adjusting block is adapted to slide in guideways 22 formed in the inner surfaces of the body walls at the upper or smaller end of said oar lock body.

In actual practice the adjusting block and threaded rod may be produced as one element and in the form of a screw, wherein said adjusting block becomes the head of the screw but is flat and narrow relative to the body of the oar lock.

One end of each of a pair of chains 23, or the equivalent thereof, such as flexible cables, are attached to the adjusting block 21 either directly or through the medium of a ring 24 which is passed through the end links of the chains and through a hole in the adjusting block. It will be obvious that wherever chains are referred to it means either two separate chains or the two sections of a single chain.

The opposite ends of the chains 23 are attached at spaced locations adjacent the ends of the flanges 25 of the clamp or cradle 26, and like the connection of the chains with the adjusting block, said chains may be connected directly with the clamp or cradle or they may be attached to rings 110.

27 passing through holes in the clamp flanges and through the lower end links of the chains.

6 The clamp or cradle 26 includes an elongated round or tubular body 28 which will be caused to firmly grip the loom of the oar 29 as said body is contracted through the medium of any suitable fastening means, such as a bolt 30 passed through the flanges of the clamp with a nut 31 screwed thereon for drawing said flanges toward 10 each other, thereby contracting the body of the clamp.

With the parts mounted on a boat as shown in Figs. 1 and 2, the oar may be used in the ordinary manner with a minimum of friction so 15 that practically all of the force applied to the oars will be utilized in propelling the boat and when the oars are released for any reason whatever they will remain fastened in the oar locks, and if found desirable, the oars may be so positioned in the clamps as to have any desired "balance" best suited for the person using the oars. Also, if desirable, the oars can be so balanced 20 that when released by the person using the same, they will assume a horizontal position with the blades of the oars actually out of the water, which is sometimes an advantage.

Whenever the oars are to be removed from the oar locks without the latter being removed from the boat, the nuts 20 are simply backed off so 30 as to permit the adjusting blocks 21 and their threaded rod or screw portions to be withdrawn, and since the bodies of the oar locks are much larger than the handle ends of the oars, the latter may be withdrawn from the oar locks, but 35 when it is desired to remove the oar locks as well as the oars, the set screws 14 can be partly backed out and the oar lock shanks withdrawn from the sockets without disturbing the relation of the oar locks to their respective oars.

40 Of course we do not wish to be limited to the exact details of construction herein shown and described as these may be varied within the limits of the appended claims without departing from the spirit of our invention.

45 Having thus fully described our invention, what we claim as new and useful is:—

1. An oar lock having an oval body to receive an oar with the smaller end of said body uppermost, an adjusting block slidably mounted in the upper end of said oar lock, a screw by which 50 said block is carried passing through the upper end of the oar lock, a nut threaded on said screw and engaging the oar lock to hold the block in place, and flexible suspension means for an oar connected with said adjusting block.

55 2. A safety oar lock and suspender having a closed eye with a hub at one end, the walls of said eye having oppositely disposed vertical guideways therein adjacent the hub, an adjusting block slidably mounted in the guideways, a screw portion carried by said block and passing through the hub, a nut screwed on the projecting end of 60 said screw part, an oar clamp for suspension within the eye, and flexible means connected to the ends of said clamp and to the adjusting block.

3. In a device of the kind described, an oval shaped body forming a closed eye, the inner faces of the walls of said body having oppositely located vertical guideways at the smaller end, a screw provided with a head functioning as an 80 adjusting block with the threaded portion projecting through the smaller end of the body and the ends of the head registering with the guideways, a nut on said screw engaging the body to draw the adjusting block upward, and means for hanging an oar from the adjusting block within 85 the oar lock body.

4. In a device of the kind described, an oval shaped body forming a closed eye, the inner faces of the walls of said body having oppositely located vertical guideways at the smaller end, a screw provided with a head functioning as an 90 adjusting block with the threaded portion projecting through the smaller end of the body and the ends of the head registering with the guideways, a nut on said screw engaging the body to draw the adjusting block upward, a clamp including an elongated longitudinally split body to receive an oar and a pair of parallel contiguous flanges along the edges of the split, means to 95 draw the flanges toward each other for contracting the body about the oar loom, and flexible means connected with the flanges at the ends of the clamp and with the adjusting block.

5. In a device of the kind described, an oval shaped body forming a closed eye, the inner faces of the walls of said body having oppositely located vertical guideways at the smaller end, a screw provided with a head functioning as an adjusting block with the threaded portion projecting 105 through the smaller end of the body and the ends of the head registering with the guideways, a nut on said screw engaging the body to draw the adjusting block upward, a clamp including an elongated longitudinally split body to receive an oar 110 and a pair of parallel contiguous flanges along the edges of the split, means to draw the flanges toward each other for contracting the body about the oar loom, a ring carried by the adjusting block, other rings carried by the flanges of the 115 clamp, one at each end thereof, and chains connected with the rings for suspending the cradle and the oar therein within the oar lock.

6. A device of the character described comprising a socket member having a screw threaded 120 therein, a body formed to provide a closed loop and a depending shank with a circular groove thereabout, said shank being seated in the socket and the inner end of the screw projected into the groove to prevent accidental displacement 125 of the body, said body being so formed that the closed loop is of oval shape with the smaller end uppermost, a clamp to be fastened about the loom of an oar, chains connected to the ends of said 130 clamp, and means removably mounted in the 135 smaller end of the body to which said chains are also connected.
